(57) **CLAIM**

We claim the ornamental design for a ventilated vacuum commutation structure, as shown and described.

DESCRIPTION

FIG. 1 is a perspective view of a ventilated vacuum commutation structure;

FIG. 2 is a first side view of the ventilated vacuum commutation structure;

FIG. 3 is the second side view of the ventilated vacuum commutation structure;

FIG. 4 is a top view of the ventilated vacuum commutation structure;

FIG. 5 is a bottom view of the ventilated vacuum commutation structure;

FIG. 6 is a front view of the ventilated vacuum commutation structure; and,

FIG. 7 is a rear view of the ventilated vacuum commutation structure.
